UNITED STATES PATENT OFFICE.

HORACE P. BROWN, OF SAN FRANCISCO, CALIFORNIA.

MANIFOLDING-BLANK.

SPECIFICATION forming part of Letters Patent No. 760,609, dated May 24, 1904.

Application filed July 10, 1903. Serial No. 165,010. (No model.)

To all whom it may concern:

Be it known that I, HORACE P. BROWN, a citizen of the United States, residing at San Francisco, in the county of San Francisco and State 5 of California, have invented certain new and useful Improvements in Manifolding-Blanks, of which the following is a specification.

This blank is especially intended for shipping receipts and similar purposes requiring 10 a duplicate and triplicate copy of an original writing.

The blank consists of a single sheet perforated or weakened transversely along three lines and folded into four superposed sections. 15 Two alternate sections are coated with transfer-material on the same side of the sheet and are folded toward the intermediate uncoated section, so that one coated section overlies the other coated section. Two of the sections are 20 of greater width than the other sections to provide a margin by means of which several of the blanks may be bound into a tablet or pad and to enable these sections when separated to be conveniently secured in a file-holder. 25 The invention will be more readily understood by reference to the accompanying drawings, in which—

Figure 1 is a perspective view of one of the folded blanks partly opened to show the arrangement of the sections. Fig. 2 is a perspective view of a blank with the sections folded in a somewhat different manner. Fig. 3 is a plan view of one side of the sheet prior to folding it, and Fig. 4 is a plan view of the 35 other side of the unfolded sheet.

The blank consists of a single sheet 1, which is perforated or weakened transversely along three lines 2 3 4 to provide four sections 5 6 7 8. Two alternate sections, here numbered 40 5 and 7, are coated on the same side of the sheet with a hard carbon compound or other usual transfer material. Section 5 is shown as printed on its uncoated face to provide a memorandum shipping-receipt marked "Duplicate." That face of section 6 lying between the coated faces of sections 5 and 7 is printed to constitute the original shipping-receipt, marked "Original." The face of section 7 opposite to that which is coated is here shown 45 blank, but may contain any desired printed 50

matter. The face of section 8 on the side of the sheet which carries the coatings is printed as a shipping-order and is marked as such. The sections 5 and 6 are of somewhat greater width than the sections 7 and 8 to provide 55 binding margins 5' 6'. These margins are shown punched or perforated to enable the detached sections to be easily secured in a file-holder or placed on a file-hook without mutilation. The sheet is folded along the lines 60 2 and 3 by turning the coated faces of the sections 5 and 7 toward the intermediate section 6. The coated face of section 5 is shown in Fig. 1 as folded directly upon the printed face of section 6, thus providing the wider **V** fold, 65 the coated face of section 7 then folded down upon the printed face of section 5, and finally the blank or rear face of section 8 folded upon the uncoated face of section 7. It will be seen that the sheet is thus folded into a double **V**, 70 one **V** fold being narrower than and lying upon the other **V** fold.

In Fig. 2 the coated face of section 7 is shown folded directly upon the printed face of section 6. The blank or rear face of section 8 is 75 then folded down upon the uncoated face of section 7. The coated face of section 5 is finally folded upon the printed face of section 8. The appearance of the blank thus folded is precisely similar to that of Fig. 1, except 80 that the narrower **V** lies within instead of upon the wider **V** fold. The arrangement shown in Fig. 1 is preferable, since the shipping-order, section 8, can be easily and quickly raised by a drawing motion of the left-hand 85 thumb, to permit the introduction of a stop-card or writing-surface.

A number of the folded blanks may be detachably bound together into a tablet or pad by means of the marginal extensions 5' 6'. 90 This result is preferably effected by simply gluing a strip of cloth or paper to the edge of the binding margins of the several blanks.

In using the blanks a stop card or sheet of stiff paper is inserted beneath the blank to be 95 filled out and the desired memorandum is written upon the top section. The transfer material on the back of the coated sections then reproduces the writing on the face of the duplicate and triplicate sections. The blank 100

may then be detached and the sections torn apart, or it may be retained in place and simply turned back to enable another blank to be filled out.

5 By the use of this blank two copies with clean or uncoated backs are afforded, while the third copy, having a coated back, may be retained as a memorandum. The intermediate coated section may be thrown away or utilized 10 as an interleaving carbon-sheet. The carbon coating on the back of two of the sections dispenses with the use of troublesome loose carbon-sheets. The provision of transfer material on one side of the sheet only enables the 15 sheet to be suitably coated by passing it but once through the coating-machine.

I claim—

1. A manifolding-blank, consisting of a sheet perforated or weakened transversely 20 along three lines to provide four sections, alternate sections coated with transfer material on one face of the sheet and folded toward the intermediate uncoated section so that one coated section overlies the other coated section, as set forth.

2. A manifolding-blank, consisting of a sheet folded into four superposed sections, two sections having transfer material on their back, and two sections being of greater width. 30 than the other sections to provide binding margins, as set forth.

3. A manifolding-blank, consisting of a sheet folded into four superposed sections, two sections having transfer material on their back, and two adjacent sections being of greater width than the other sections to provide a folded binding portion, as set forth.

4. A manifolding-blank, consisting of a sheet perforated or weakened transversely 40 along three lines to provide four sections, alternate sections coated with transfer material on one face of the sheet and folded toward the intermediate uncoated section so that one coated section overlies the other coated section, and two sections being of greater width 45 than the other sections to provide binding margins, as set forth.

5. A manifolding-blank, consisting of a sheet perforated or weakened transversely 50 along three lines to provide four sections, alternate sections coated with transfer material on one face of the sheet and folded toward the intermediate uncoated section so that one coated section overlies the other coated section, and two adjacent sections being of greater 55 width than the other sections to provide a folded binding portion, as set forth.

6. A triplicate manifolding-blank, consisting of a sheet perforated or weakened transversely 60 along three lines to provide four sections, the first and third sections coated with transfer material on one face of the sheet, the first section having a printed triplicate form on the uncoated face of the sheet and the second and fourth sections having printed trip-

65 licate forms on the coated face of the sheet, as set forth.

7. A manifolding-blank, consisting of a sheet perforated or weakened transversely 70 along three lines to provide four sections, alternate sections being coated with transfer material on one face of the sheet, the coated end section being folded upon the intermediate uncoated section, the intermediate coated section folded upon the coated end section, 75 and the uncoated end section folded back upon the intermediate coated section, the folded blank thus consisting of two **V** folds, one lying upon the other, as set forth.

8. A manifolding-blank, consisting of a sheet perforated or weakened transversely 80 along three lines to provide four sections, alternate sections being coated with transfer material on one face of the sheet, the coated end section being folded upon the intermediate 85 uncoated section, the intermediate coated section folded upon the coated end section, and the uncoated end section folded back upon the intermediate coated section, the folded blank thus consisting of two **V** folds, one lying 90 upon the other, and two sections being of greater width than the other sections to provide binding margins, as set forth.

9. A manifolding-blank, consisting of a sheet perforated or weakened transversely 95 along three lines to provide four sections, alternate sections being coated with transfer material on one face of the sheet, the coated end section being folded upon the intermediate uncoated section, the intermediate coated section folded upon the coated end section, 100 and the uncoated end section folded back upon the intermediate coated section, the folded blank thus consisting of two **V** folds, one lying upon the other, and two adjacent sections being of greater width than the other sections to provide a folded binding portion, as set forth.

10. A manifolding-blank, consisting of a sheet perforated or weakened transversely 110 along three lines to provide four sections, alternate sections being coated with transfer material on one face of the sheet, the coated end section and the adjacent uncoated section being of greater width than the other two sections 115 to provide a folded binding portion, the coated end section being folded upon the intermediate uncoated section, the intermediate coated section folded upon the coated end section, and the uncoated end section folded back 120 upon the intermediate coated section, the folded blank thus consisting of two **V** folds, of different width, the narrower one lying upon the wider one, as set forth.

In testimony whereof I affix my signature in 125 presence of two witnesses.

HORACE P. BROWN.
